UNITED STATES PATENT OFFICE.

WILMUTH E. BLACKBURN, OF SUMMIT, NEW JERSEY.

GAME APPARATUS.

1,279,637.

Specification of Letters Patent. Patented Sept. 24, 1918.

Application filed August 21, 1917, Serial No. 187,327. Renewed July 10, 1918. Serial No. 244,337.

To all whom it may concern:

Be it known that I, WILMUTH E. BLACKBURN, a citizen of the United States, and resident of Summit, in the county of Union 5 and State of New Jersey, have invented certain new and useful Improvements in Game Apparatus, of which the following is a specification.

This invention relates to improvements in 10 game apparatus, and has for its general object to furnish a game to be played with a ball or projectile, in which both skill and chance will play a part and the operator will derive great amusement therefrom.

15 The invention consists essentially of the novel construction and arrangement of parts whereby a ball or other projectile, after rolling along an inclined track, is deflected upwardly and trajectory from the end 20 thereof and, during its flight, is adapted to contact with a baffle and to be deflected thereby into one or the other of a series of goals comprising a target.

25 Referring to the drawings forming a part of this specification, in which like numerals designate like parts in all the views;

Figure 1 is a top plan view of my game apparatus with a part broken away for the sake of clearness.

30 Fig. 2 is a longitudinal sectional view thereof, and

Fig. 3 is a cross-sectional view thereof taken on the line 3—3 of Fig. 2.

The game consists of a frame 1 within 35 which is mounted a ball track 2 along which the balls 3 are rolled when the game is in operation. In the drawings, the frame is shown as inclosing three separate game appliances, so that three different players may 40 play the game at one time. As all of the appliances are exactly alike, only one will be described.

The track is downwardly inclined from 45 the counter or playing end of the appliance, and has its delivery end provided with an upturned portion 5 which causes the balls, when leaving the track, to be projected upwardly into the air. To prevent the balls from leaving the track during their travel 50 down the incline, the track is provided with the side rails 6.

Spaced a suitable distance from the end 55 of the track and located within the opposite end of the frame 1 is a target 7. This target consists of a vertical wall 8, adapted to support a plurality of goals in the form

of small pockets 9, a large central pocket 10, and an apertured sloping shelf 11, into one of which it is the object of the player to direct the ball. The several pockets and 60 apertures in the shelf have each their own relative value and the player scoring the highest value in one or more plays wins. These goals are situated one above the other and, being of various sizes and arrangements, they may be numbered accordingly, the uppermost one preferably having the greatest value in scoring. The small pockets 9 are each provided with an opening 12 which openings lead to a compartment 13 65 formed in the rear of the target between the inner wall 8 and the outer wall 14 forming the end of the frame. This compartment 13, as shown by dotted lines in Fig. 3, is in communication with an inclined runway 15 which returns the balls to the receiving compartment 16 located beneath the counter at the playing end of the appliance. The large pocket 10 is also provided with an opening 17 which leads to a second compartment 70 75 80 formed between the walls 8 and 14. By means of a pair of openings 19, arranged in the wall 8 and located below the pocket 10, this second compartment 18 is placed in communication with the upper 85 surface of the shelf 11 which forms the lowermost goal of the target. The shelf projects outwardly from the wall 8 and is downwardly inclined therefrom so that a ball in being directed thereon will roll over 90 its upper surface and find its way into any one of the series of holes 20 of relatively different diameters provided in the shelf. After passing through the holes 20, the balls are then directed to the inclined runway 15 95 which returns them to the receiving compartment 16 beneath the counter and from whence they may be readily obtained by a player when desired.

A baffle 21 is mounted on the frame above 100 the target and is arranged in the path of movement of the trajectory balls so that the balls in striking the baffle may be deflected toward the target. The baffle, which is in the form of a board, bridges the side walls 105 of the frame and is horizontally inclined downwardly toward the discharge end of the track so that it will direct the balls rearwardly.

In playing the game, each player uses an 110 appropriate number of balls. The player places these balls, one after another, on the

upper end of the inclined track and the balls are permitted to roll down the track by gravity and are projected upwardly into the air by means of the upturned portion 5 at the discharge end of the track. During its flight, each ball strikes the baffle and is deflected thereby toward the target and it is the intention that it be directed into one of the smaller goals, preferably the central 10 uppermost goal which has the greatest value in scoring. Should the ball miss one of the smaller goals, it may be directed into the larger central goal, from which it will be directed through the compartment 18 onto 15 the shelf where it will fall through one of the openings arranged thereon and find its way through the runway back to the receiving compartment 16.

It is obvious that those skilled in the art 20 may vary the details of construction and arrangement of parts without departing from the spirit of my invention and, therefore, I do not wish to be limited to such features except as may be required by the claims.

25 What I claim is:—

1. A game apparatus, comprising a ball track inclined upwardly at the delivery end for trajecting a ball therefrom, an apertured target spaced from the end of said track and 30 a baffle arranged in the path of movement of a trajected ball for deflecting the ball toward said target.

2. A game apparatus, comprising a ball track inclined upwardly at the delivery end

for trajecting a ball therefrom, an apertured 35 target spaced from the end of said track and a baffle mounted above said target and arranged in the path of movement of a trajected ball for deflecting the ball toward said target.

40

3. A game apparatus, comprising a ball track inclined upwardly at the delivery end for trajecting a ball therefrom, an apertured target spaced from the end of said track, and a horizontally inclined baffle mounted above 45 the target and arranged in the path of movement of a trajected ball for deflecting the ball toward said target.

45

4. A game apparatus having a target including a plurality of pockets and an inclined shelf arranged below the pockets and having holes of different diameters, a ball track spaced from the target and inclined upwardly at the delivery end for trajecting a ball therefrom, and an inclined baffle 50 mounted above the target and arranged in the path of movement of a trajected ball for deflecting the ball toward said target.

50

5. A game apparatus comprising a ball track having an upwardly inclined portion 60 for trajecting a ball therefrom, a target at the rear of said track and a baffle arranged in the path of movement of the trajected ball for deflecting the ball toward said target.

60

Signed at New York, in the county of New 65 York and State of New York, this 17th day of August, A. D. 1917.

WILMUTH E. BLACKBURN.
